GARAGE DOOR HOLDER

John E. McJimsey, Larkspur, Calif.

Application September 8, 1944, Serial No. 553,220

2 Claims. (Cl. 292—121)

This invention relates to new and useful improvements in holders for garage doors, the principal object being to provide a simplified and quick-acting holder for holding garage doors open while an automobile is either being brought into the garage or taken out.

Another important object of the invention is to provide a garage door holder which can be manufactured at low cost and which because of its sturdy construction will be durable and not as much liable to encourage defects as devices of this character now in general use.

Other objects and advantages of the invention shall become apparent to the reader of the following description.

In the drawing:

Figure 1 is a fragmentary side elevational view of the holder.

Figure 2 is a top plan view of the holder.

Figure 3 is a fragmentary rear elevational view of the holder.

Referring to the drawing wherein like numerals designate like parts, it can be seen that numeral 5 denotes a stake of angle construction, the same having right angular flanges a, b.

On the upper portion of the stake 5 is disposed an angle plate 6 which at one vertical edge has a bolt hole receiving a bolt 7, this bolt also extending through a clamp plate 8 at the opposite side of the flange b of the stake 5 in order to clamp the angle plate 6 firmly in position. The bolt 7 has a nut 9 and an overlapping lip 10.

The remaining vertical edge portion of the plate 6 has a pair of vertically spaced openings therein for receiving bolts 11 which extend through openings in clamp plates 12 at the opposite side of the stake 5 from the plate 6, thus clamping this edge portion of the plate 6 firmly in position on the stake. The clamp plates 12 having lateral lips 13 which bear against the inner side of the angle plate 6.

The clamp plates 12, 12 are vertically spaced as shown in Figure 1 and between these plates a pivot member 14 is disposed through the angle plate 6 and through the depending flange c of an elongated angle arm 15 which has a top horizontal flange d. Numeral 16 denotes a coiled tension spring interposed between the lower portion of the angle plate 6 and the rear end portion of the angle arm 15 for normally holding the angle arm in a substantially horizontal position as shown in Figure 1.

The forward end of the arm 15 has an incline

17 which rises to a point 18 substantially above the flange d of the arm 15.

It can now be seen, that in order to adapt the holder for use in conjunction with a garage door, the stake 5 is first driven into the ground, after which the angle plate 6 is properly adjusted to the correct elevation above the ground. The angle plate 6 is held in place by the bolts 7, 11 and the clamp plates 8, 12. When the arm 5 has been properly set, it will be seen, that when a door 19 is swung to the holder, it will strike the incline 17 and depress the forward end portion of the arm 15, tensioning the spring 16. When the door rides over the upper portion 18 of the incline, the spring 16 will move the arm 15 to its normal horizontal position, thus holding the door 19 between the rise 18 and the angle plate 6.

While the foregoing specification sets forth the invention in specific terms, it is to be understood that numerous changes in the shape, size and materials may be resorted to without departing from the spirit and scope of the invention as claimed hereinafter.

Having described the invention, what is claimed 25 as new is:

1. A door holder comprising a right angular upright, a right angular clamp on the outside of said upright, a right angular arm pivotally connected to said clamp at right angles to said upright, said arm being provided with a beveled head over which a door is adapted to ride in depressing the corresponding end of said arm, and individual clamp plates inside the edges of said upright and bolted to said right angular 30 clamp forming channels therebetween adapted to receive the edge portions of said upright.

2. A door holder comprising a right angular upright, a right angular clamp on the outside of said upright, a right angular arm pivotally 35 connected to said clamp at right angles to said upright, said arm being provided with a beveled head over which a door is adapted to ride in depressing the corresponding end of said arm, individual clamp plates inside the edges of said upright and bolted to said right angular clamp forming channels between said individual clamps and said right angular clamp adapted to receive the edge portions of said upright, and a coil spring 40 having one of its ends secured to said right angular clamp and the other end secured to said angular arm for returning the arm to normal position.

JOHN E. McJIMSEY.
